INJECTOR

Eugene Y. Guthmann, Philadelphia, Pa.

Application November 12, 1938, Serial No. 249,161

7 Claims. (Cl. 103—265)

This application is in part a continuation of my copending application Serial Number 72,635, which issued August 12, 1940, as Patent No. 2,211,058.

A principal object of the invention herein disclosed is to provide an injector of the exhaust steam type of generally improved structural and functional characteristics.

More specifically, an object of the invention is to provide an injector of the stated type that shall be characterized by relative simplicity of mechanical structure and assembly, compactness of form and high functional efficiency.

Still more specifically, an object of the invention is to provide an improved injector of the stated type that shall be operative automatically to utilize steam from the exhaust source to the exclusion of the live steam at such times as the said exhaust steam may be available in sufficient quantities to meet the requirements of the injector.

Another object is to provide a device of the stated character wherein the control of all the fluids involved shall be accomplished automatically through the medium of a single movable member affording a unified and exactly synchronized interregulation of the flow of the fluids in the injector.

Still another object of the invention is to provide an injector of the stated type and mode of operation wherein all operating parts including the mechanism for automatic selective control and interregulation of the various fluids shall be combined in a single compact and highly efficient unit.

A further object of the invention is to provide an exhaust steam injector in the form of a unitary device wherein the parts are arranged about and operate along a common axis or center line.

Another object of the invention is to provide an exhaust steam injector comprising means for utilizing live or exhaust steam for forcing and heating purposes, and comprising also within itself means for automatically controlling and regulating the water supply and for selectively controlling the flow of steam from the different sources and to different points, as hereinafter described.

A still further object is to provide an injector of the character set forth in the preceding paragraphs the operation of which as regards starting and stopping may be controlled through the medium of a single manual control member, or at most through the medium of a main and a single supplemental control member.

The invention further resides in certain novel and advantageous structural and functional devices and arrangements hereinafter described, and illustrated in the attached drawings, wherein:

Fig. 1 is a vertical sectional view showing an injector device made in accordance with the invention;

Fig. 2 is a detached view in perspective of one of the elements of the mechanism;

Figs. 3, 4 and 5 are, respectively, vertical sectional views illustrating the device in various positions of automatic adjustment;

Fig. 6 is a fragmentary view showing a detail of construction;

Fig. 7 is a fragmentary sectional view illustrating a modification within the scope of the invention;

Fig. 8 is a vertical sectional view illustrating the invention as applied to another type of injector;

Fig. 9 is a vertical sectional view of the fluid supply means of a single line injector made in accordance with my invention;

Fig. 10 is a fragmentary view showing a detail of construction, and

Fig. 11 is a fragmentary sectional view illustrating a modification within the scope of the invention.

With reference to Figure 1 of the drawings, the injector feed water heater therein illustrated comprises a casing 1 having ports 2 and 3 adapted for connection to sources of water and exhaust steam respectively. The casing comprises a flanged head 4 having a depending cylindrical extension or bushing 5 which projects downwardly into the interior of the casing and which terminates at its lower end in a tapered extremity 6. The bushing 5 is hollow and receives for sliding adjustment in its cylindrical bore a sleeve 7, said sleeve embracing a cylindrical duct 8. The lower solid extremity 9 of the duct 8 is secured in the tapered end 6 of the bushing 5 by means of a set screw 11, and the upper end of the duct projects through the head 4 of the casing and is provided with a union 12 by means of which the duct may be connected with a source of live steam. The upper end of the duct 8 where it passes through the head 4 is embraced by a bushing 13, said bushing being threaded into the head and being secured in predetermined adjusted position by means of a lock nut 14. The inner end of the bushing 13 forms an abutment for an upper spring seat 15, and anti-friction bearings 16 are interposed between the seat 15 and the opposed

end of the sleeve. The seat 15 receives one end of a coiled spring 17, which embraces the duct 8 and which seats at its lower end upon the sleeve 7, said sleeve being provided at its upper end with an extended recess 18 for reception of the spring. The spring 17 urges the sleeve 7 downwardly into the normal position in which it is shown in Figs. 1 and 7, and the pressure of the spring against the sleeve may be regulated in obvious manner through the medium of the bushing 13.

The sleeve 7 carries a transverse pin 19, the mid portion 20 of which is provided with an opening through which extends the duct 8. The outer ends of the pin 19 project through slotted openings 21, 21 in opposite sides of the bushing 5, through apertures 22 in anvil elements 23, see also Fig. 2, which are fitted slidably in the slotted openings 21 of the bushing 5, and terminate in an outer sleeve 24 which closely embraces the enlarged mid portion 25 of the bushing 5 and which has at its lower end a tapered extremity 26 which surrounds the tapered extremity 6 of the said bushing. The anvils 23, as shown in Fig. 2, are shaped to conform to the cylindrical surfaces of the sleeves 7 and 24, between which they are closely confined with their flanged head portions 27 in engagement with the upper end surface of the sleeve 24. The pin 19 unites the inner and outer sleeves 7 and 24 and the anvils 23 into a unitary structure adapted for sliding adjustment within the casing.

Intermediate its ends the sleeve 24 is provided with a section 28 of increased diameter forming a shoulder 29 which seats upon the upper end of a combining tube 31, this tube being suitably mounted within the casing and extending downwardly through the area of the port 2 to terminate at its lower end in a tapered extremity 32. The shoulder 29 by seating upon the combining tube 31 limits the downward movement under the action of the spring 17 of the sleeve 24, and hence of the sleeve 7 to which it is attached as previously described through the medium of the pin 19. The lower end of the sleeve 24 fits neatly within the upper end of the combining tube 31 and has formed thereon a shoulder 33, which preferably, in the depressed position of the sleeve 24, seats upon a reverse shoulder formed in the tube 31, as illustrated in Fig. 1. The port 2 of the casing 1 communicates with a chamber 34, the inner wall of which is formed by the tube 31, and the said tube is provided around its circumference with a series of ports 35 which communicate with the chamber 34 and which are normally closed by the lower end of the sleeve 24, as illustrated. The tapered extremity 32 of the combining tube is provided externally with longitudinal ribs 36, and between these ribs with ports 37 which, conventionally, provide for overflow of water from the tube to the overflow or suction chamber 38.

Suitably mounted in the interior of the casing 1 within the area of the port 3 is a sleeve 39, the lower end of which is perforated, as indicated at 41, and this sleeve also is provided with an inwardly offset depending flange 42, which may be similarly perforated if desired and which lies in proximity to the outer surface of the sleeve 24. The port 3 communicates with a chamber 43 which embraces the sleeve 39, and this chamber is in communication with the annular chamber 44 in the interior of the sleeve 39 through the apertures in the lower end of the said sleeve and the space between the flange 42 and the sleeve 24.

The tube 8 is provided with a port 45 which normally registers with the upper end of a port 46 in the sleeve 7 which extends from the inner face of this sleeve downwardly therethrough to the lower end. The ports 45 and 46 thus establish communication between the interior of the tube 8 and the chamber 47 formed between the lower end of the sleeve 7 and the lower end of the interior bore of the bushing 5. From this chamber 47 a port 48 of restricted cross sectional area extends through the lower tapered end 6 of the bushing 5 to the outer surface thereof. The sleeve 7 is also provided with a port 49, which when the said sleeve is elevated, as hereinafter described, to a predetermined extent is adapted to register with and establish connection between a port 51 in the wall of the tube 8 and a port 52 in the bushing 5. This port is formed directly below the enlarged mid portion 25 of the said bushing and communicates with the chamber 53 formed between the lower end of the bushing 5 and the outer sleeve 24. Registration of the port 49 with the ports 51 and 52 thus establishes a direct connection between this chamber 53 and the source of live steam. It will be noted that the port 49 and the upper end of the port 46 are in substantial alignment, and that the upper end of the port 45 corresponds substantially to the lower side of the port 51. The bushing 5 also contains a fourth port, 54, which when the sleeve 7 has been elevated to a predetermined extent establishes direct communication between the chamber 47 and the chamber 53.

The outer sleeve member 24 has in the wall thereof a port 55 which is normally closed at the inside by the enlarged portion 25 of the bushing 5. This port 55, when the sleeve 24 has been elevated to an extent bringing the port 49 opposite the ports 51 and 52, registers with a port 56 in the bushing 5, which port communicates with the chamber 57 formed between the sleeve 7 and the upper side of the enlarged portion 25 of the bushing 5. The port 55 communicates at its outer end with the chamber 44, which as previously set forth is in communication with the apertures in the lower portion of the sleeve 39 and with the chamber 43 which communicates with the port 3. The sleeve 24 also contains a pear-shaped port 58, see Figures 3, 4 and 5, arranged to register in predetermined positions of the sleeve 24 with a port 59 in the bushing 5 communicating at its inner end with the chamber 57.

Also provided in the sleeve 24 is a circumferential series of ports 61 which when the sleeve 24 occupies a normal depressed position as shown in Figs. 1 and 3 are closed at the outer side by the combining tube 31. When the sleeve 24 is elevated to a predetermined extent, these ports 61 establish communication between the port 3 and the chamber 53.

Insofar as described, the operation of the device is as follows: With the parts in the positions shown in Figs. 1 and 3, it will be noted that the ports 35 and 61 being closed, both water and exhaust steam are excluded from the combining tube 31. Also exhaust steam if present in the chambers 43 and 44 is excluded from the chamber 57. The spring 17 tends to hold the movable parts in the depressed positions, and the exhaust steam not only has no tendency to elevate these parts against the pressure of the spring 17, but actually exerts a pressure at the upper surfaces of the anvils 23 and the sleeve 24 tending to hold the moving parts in the depressed position. If, now, live steam is admitted to the duct

8, this steam passing to the chamber 47 through the ports 45 and 46 will exert pressure against the lower end of the sleeve 7 tending to elevate this sleeve and with it the outer sleeve 24 from the normal positions. This elevation of the parts has two effects; first, it opens the ports 35 and establishes communication between the source of water through the port 2 and the interior of the combining tube 31, and, second, it eventually brings the port 49 into registration with the ports 51 and 52 so that live steam will pass from the tube 8 into the chamber 53 and downwardly through the tapered lower end 26 of the sleeve 24 into the combining tube 31. The effect of this steam discharging into the combining tube 31 is to heat the water entering the tube 31 through the ports 35. It will be noted that the arrangement provides by selection of the number, location and size of the ports involved in the operation described above a thorough regulation of the flow of live steam and water to the combining tube, and this factor, coupled with the simultaneous and unified control of the water and steam inflow, provides for delivery of these elements to the combining tube in accurately controlled ratio to afford the most efficient, economical and stable operation. With a device of this character, it is unnecessary to have any means for independent control of the water from the source.

Attention is directed to the live steam lift chamber 47 and the manner in which steam is admitted thereto. The drain port 48 is smaller than the supply port 46, this permitting a gradual increase of pressure in the chamber avoiding too sudden lift of the moving parts. The length of the lift is determined by the length of the port 45 in the direction of movement, and is definitely limited by the pressure-equalizing port 54, which as previously described is opened when the sleeve 7 has reached a predetermined elevation corresponding substantially to the length of the port 45. The port 54 functions to permit an escape of excess pressure in the chamber 47 and precludes upward movement of the sleeve 7 under the action of the live steam beyond the limits of the port 45. Preferably this latter port is restricted towards its upper end after the manner illustrated in Fig. 6, so that as the sleeve 7 rises, the effective area of the port is gradually decreased. This gradual reduction in area of the supply port and the fact that the drain port 48 is eventually supplemented by the equalizing port 54 makes possible the maintenance in the chamber 47 of an effective pressure substantially equal to the weight of the moving parts and the counter pressure imposed by the spring 17, so that a definite line or lift level may be established.

The initial lift thus effected by the live steam brings the ports 61 to a position at the top of the combining tube 31, wherein an additional lift will effect the opening of these ports to establish connection between the port 2 and the chamber 53. Also the initial lift as previously set forth brings the port 55 into registration with the port 56, and thereby admits exhaust steam, if present in the chamber 44, to the secondary lift chamber 57. If exhaust steam is present in sufficient quantity to further lift the sleeves 7 and 24 against the pressure of the spring 17 and the counter exhaust steam pressure upon the moving parts, there results an immediate closing of the live steam ports 45 and 51 and an opening of the ports 61 admitting the exhaust steam to the chamber 53. The device is so designed that when

the supply of exhaust steam is such that the steam from this source is capable of assuming the water heating function, the live steam from the other source is automatically cut off, thereby conserving the live steam for other useful work and utilizing the waste exhaust steam for the water-heating operation.

It will be noted by reference to Fig. 4, which shows the moving parts in the "initial lift position" effected by the live steam as previously described, that the ports 58 and 59 have been brought to a position in which they are about to register. This registration, occurring when the exhaust steam further elevates the moving parts, supplies exhaust steam to the chamber 57 continuously to the point of maximum lift, as shown in Fig. 5. When the port 55 clears the upper end of the enlarged portion 25 of the extension 5, this port also admits exhaust steam to the chamber 57. Preferably the port 58 is of inverted pear-shape, as shown in Figs. 3, 4 and 5, so that there is a gradual reduction in the supply of exhaust steam to the chamber 57 toward the upper end of the stroke, thereby throttling the admission of the exhaust steam to the chamber and precluding undue shock at the upper end of the stroke. In this secondary lifting of the moving parts by the exhaust steam, the ports 61 are opened to admit exhaust steam to the chamber 53, from whence it passes through the tapered lower end 26 of the sleeve 24 into the tube 31 for combining with the water admitted to this tube through the ports 35. In this secondary lift also, there is a simultaneous and automatic regulation of the flow of the water and exhaust steam as in the previously described primary lift employing live steam with the same attendant advantages.

It will be noted further by reference to Fig. 5 that the regulation of the exhaust steam ports during the secondary lift is effected in part by the overlapping of these ports with the enlarged portion 25 of the bushing 5. The extent to which in the extreme elevated position of the moving parts the ports 61 are closed may differ from that shown in Fig. 5, it being possible by increasing or decreasing the travel in the upward direction of the moving parts to vary the ultimate areas of the ports 61 exposed for steam admission or to completely close them. It is apparent that with this arrangement of ports it is possible to obtain a well controlled and regulated flow of water and exhaust steam to the combining tube calculated to afford the most efficient results.

If at any time the supply of exhaust steam fails or is reduced to a point where it is inadequate for the water-heating function, the device will automatically adjust itself for continued operation from the live steam source. Thus when the parts by reason of the failure of the exhaust steam move under the action of the spring 17 toward the normal depressed position, the ports 61 are cut off and the port 49 simultaneously returned to registration with the ports 51 and 52, admitting live steam to the chamber 53. The operation of the device may be discontinued entirely either by shutting off the supply of live steam to the duct 8 in the event that the device is operating on live steam alone; or in the event that the device is operating on exhaust steam by momentarily interrupting the supply of exhaust steam and subsequently cutting off the supply of live steam to the duct 8, the parts being then returned to their normal or inoperative positions as shown in Figs. 1 and 3.

Means is also provided for manually returning the moving parts to the normal inoperative position in the event that it is undesirable or inconvenient to momentarily check the supply of exhaust steam. This means comprises a plunger rod 62 slidably mounted in the head 4 and normally occupying a retracted position as shown in Fig. 1. The plunger is arranged so that when depressed it engages the top of one of the anvils 23, so that by the application of an adequate force, the entire moving-part assembly may be forced down against the pressure of the exhaust steam into the inoperative position. When under these conditions the supply of live steam to the tube 8 is discontinued, the exhaust steam is ineffective to again elevate the parts, so that they remain in the inoperative position. In this respect, attention is directed to the shoulder 29 of the outer sleeve 24 which normally seats as described upon the upper end of the combining tube 31. When so seated, the effective pressure area of the moving-part assembly exposed to exhaust steam is that provided by the top surface of the outer sleeve 24 and the anvils 23, the steam pressure upon this area tending to retain the parts in the normal inoperative position. If this area is larger than the lift area of the moving-part assembly exposed in the chamber 57, the exhaust steam, even though admitted to the latter chamber, will not be effective to elevate the parts from their normal or inoperative position. The excess area subjected to counter pressure preventing the lift by exhaust steam under these conditions is neutralized by the pressure of the live steam in the initial starting chamber 47. When the sleeve 24 is elevated from the normal position, however, the shoulder 28 forms a lift area exposed to the exhaust steam, which also neutralizes a portion of the counter pressure area at the top of the sleeve. In every instance the total of the effective lift areas exposed to the exhaust steam pressure when the moving-part assembly has been initially elevated must be in excess of the effective counter pressure areas exposed under these conditions to exhaust steam. While in embodiments of my invention such as shown in Fig. 1 the operation does not necessarily depend upon the function of the shoulder 29 as a supplementary lift area, this function of the shoulder may be utilized to advantage in other embodiments of the invention, one of which will be hereinafter described.

Attention is directed to the central tapered element 6 at the lower end of the bushing 5. It will be noted that as the sleeve 24 is elevated the space between this sleeve and the part 6 becomes progressively more restricted, such restriction having a throttling effect upon the steam, and particularly the exhaust steam, passing from the source to the combining tube. The shape and dimensions of this tapered part, therefore, constitutes one of the factors of control and regulation of the operating pressures, and may vary in accordance with the specific requirements. Attention is also directed to the channel or port 63 and the cock 64 associated therewith which provides a means for bleeding the condensate from the exhaust steam chambers.

From the foregoing description the application of the device as a feed water heater in connection with an injector for locomotive and other engines will be apparent. The heated water is delivered from the combining tube to the forcing tubes of the injector in well known manner, the

latter tubes being operated in the conventional manner from the live steam source. When used for this purpose, the device will operate automatically for all conditions under which an additional supply of water to the boiler may be required. If, for example, the locomotive is standing so that only live steam is available for the water-heating function, the device is capable of operating efficiently with steam drawn from 10 that one available source. If the locomotive is moving and working steam, the device once started by application thereto of the live steam will automatically change over to the exhaust steam, which is available under these conditions. 15 The device is automatically operative to deliver steam under conditions wherein the supply of exhaust steam is erratic, such for example as when the locomotive is intermittently stopped and started, or when in motion, the steam intermittently is being worked or not worked. This latter condition may prevail for example when the locomotive is drifting. Under these conditions the device will automatically change over from live steam to exhaust steam operation when 20 steam from the latter source is available and will return itself to the live steam position during those periods when the exhaust steam is not available. Under any of these conditions, the device may readily be thrown into or out of operation by the operator as demanded by the water requirements. This extremely flexible range of automatic operation, which is a characteristic peculiar to my device, is made possible in large part by provision of the means for simultaneous control of water and steam operated by 25 and subject to the pressure control of the steam from the exhaust source.

It is evident that the greater the pressure of the exhaust steam, the heavier will be the drain on the water in the boiler. Under these conditions of available exhaust steam at high pressures, the automatic regulation of the ports 35 as described above will afford an increased supply of water through the injector to the boiler, 40 and thereby compensates for the excessive drain. It will be apparent also that while the heater is operating solely with live steam, opening of the ports 35 is considerably reduced, say to the minimum capacity of the injector but sufficient 45 to supply the required amount of water to the boiler under these conditions. As the exhaust steam becomes available, the device automatically adjusts itself to the increased drain upon the boiler, and under extreme conditions of drain will deliver water to the full capacity of the injector. This action materially helps the operator in maintaining a satisfactory water level in the boiler. Simultaneous control of the water and steam also contributes materially to the economical operation and stability of the injector as previously set forth.

It will be noted further that during those periods of relatively great exhaust steam pressure when the supply is in excess of that required for heating the inflowing water, there is provision for automatic throttling of the exhaust steam supply to the combining tube. Such a condition might prevail for example when the wheels of the locomotive slip on the rails under difficult haul conditions. The excessive exhaust steam pressure then elevates the sleeve 24 to a point where the normal areas of the ports 61 are reduced by ring 25 of the bushing 5 and creates a further throttling effect between the lower end of the sleeve and the extremity 6 of

the bushing. At the same time the water ports 35 are given their maximum opening. This automatic regulation maintains a proper relation between the water and steam supplies and insures a continued efficient operation under the extreme conditions.

Particular attention is directed to the fact that the moving parts of the device are limited in effect to a single member or unit consisting of the sleeves 7 and 24, the pin 18 and the anvils 23, and that the movement of this assembly or unit is in a straight line corresponding to the longitudinal axis of the device. As a result, the device is extremely compact and symmetrical and free from structural complications. In this arrangement, the ring 25 of the bushing 5 constitutes an important element. It forms a sealing partition between the live and exhaust steam sources in that it separates the secondary or exhaust steam lift chamber 57 from the live steam passing from the primary lift chamber 41 through the ports 51, 49 and 52 into the chamber 53. It constitutes in effect a solid abutment from the under side of which the live steam is directed downwardly toward the combining tube and against the upper side of the which the exhaust steam may react in the secondary lift operation.

In Fig. 7 of the drawings, I have illustrated a modified means for admitting the exhaust steam to the chamber 57. In this instance the port 55 is eliminated and is replaced by a port 65 in one end of the pin 19a. This port communicates with a channel 66 extending through the pin and through the adjoining portion of the sleeve 7. It is apparent that with this arrangement exhaust steam when available is continuously supplied to the chamber 57. Under this condition, it is essential that the counter pressure surface at the upper end of the sleeve 24 shall be of greater area than the lift pressure of the sleeve 7 exposed to the exhaust steam within the chamber 57. In this modification, the function of the shoulder 29 of the sleeve 24 as a supplementary lift area is to be noted. This area must be sufficient in extent that when added to the lift area of the sleeve 7 exposed in the chamber 57 it will increase the total effective lift area to an amount exceeding the counter pressure area at the top of the sleeve 24. It has been previously pointed out that when the moving parts occupy their normal inoperative positions, wherein the shoulder 29 seats upon the tube 31, that this area is not available for lift purposes. Under these conditions, therefore, the preponderance of the counter pressure area through which the exhaust steam tends to hold the moving parts in the inoperative position will be effective for that purpose. When, however, the moving parts are elevated initially by the live steam as described, the shoulder 29 immediately becomes effective as a lift area and combines with the lift area exposed in the chamber 57 to elevate the movable parts in opposition to the counter pressure of the exhaust steam.

In Fig. 8, I have illustrated the application of my invention to another well known type of injector. The control and regulating mechanism in this case is essentially the same as that described above, and the corresponding parts are accordingly identified by the same reference numerals. In this case, however, the outer sleeve 24 is disassociated from the water source. The steam chamber 53 communicates in this case with a chamber 68 which embraces the Venturi

tube 69 extending from the live steam inlet port 67. The chamber 68 communicates with the inner relatively large end of a tube 71 into which the discharge end of the tube 69 extends. The tube 71 in this case is mounted in the casing for axial adjustment, and this adjustment is effected through the medium of a pin 72 secured in eccentric position on the cylindrical head 73 of a shaft 74. The pin as illustrated projects into a slotted recess 75 in the outer surface of the tube 71. By rotating the shaft 74 by means of its handle 76, the position of the tube 71 with respect to the tube 69 may be varied. The water in this case is introduced into the draft chamber 77 and is combined in subsequent tubes (not shown) with the steam delivered from the chamber 68 and through the tube 69. It will be apparent that the principle of operation in this instance and insofar as concerns the apparatus forming the subject of my invention is the same as that described above in connection with the embodiment illustrated in Figs. 1 to 5, inclusive.

In addition to the functional advantages set forth above, a device made in accordance with my invention is characterized by its relative simplicity of construction and assembly and its relative dependability resulting from the superior design which provides in effect a single moving part at all times under full control and never subject to violent shocks or jars under normal operating conditions. Other advantages reside in the compact form of the device, the accessibility of the parts for inspection, and the relatively low expense of manufacture. Specifically, it constitutes a material improvement over the prior devices used for and in connection with exhaust steam injectors to supply a continuous flow of steam alternating between two sources, not only as a matter of function but also because with its relatively few parts it is capable of accomplishing results not heretofore obtainable from the relatively complex assemblies employed in the art prior to my invention.

With reference to Figs. 9, 10 and 11 of the drawings, the injector therein illustrated as an embodiment of my invention comprises a casing 81 having ports 82, 83 and 84 for admission of high pressure or boiler steam, exhaust steam and water, respectively. The port 82 leads to a chamber 85 in the upper end of the casing; the port 83 to an annular chamber 86 in the mid portion of the casing; and the port 84 to an annular chamber 87 at the lower end of the casing, this latter chamber being arranged for communication through interior ports 88 with a draft tube 89 mounted as hereinafter described in the interior of the casing.

The draft tube 89 is formed at the lower end of a sleeve 91 which has at its upper end an outwardly extending flange 92 seating on the reverse interior shoulder 93 of the casing at the bottom of the chamber 86. Seating upon the upper surface of the flange 92 is a second sleeve 94, which is threaded into the casing at 95 and which intersects the chamber 86; and the lower portion of the sleeve 94 which occupies the chamber 86 is perforated as indicated at 96 and functions thereby as a strainer for the exhaust steam which enters the casing through the port 83. It will be apparent that the draft tube sleeve 91 is clamped in place within the casing by the sleeve 94.

Mounted in the upper portion of the casing interiorly of the sleeve 94 and projecting upwardly into the high pressure steam chamber 85 is a bonnet 97, this bonnet having an outwardly ex-

tending flange 93 which seats upon a shoulder 99 in the casing and which immediately overlies the upper end of the sleeve 94. This bonnet is clamped in place by means of a follower ring 101 which is threaded into the casing as illustrated. Threaded into the upper end of the bonnet 97 is a tube or nozzle 102, the threaded end of the tube extending beyond the outer surface of the bonnet and being engaged by a lock nut 103, and the tube 102 extends downwardly and centrally through the bonnet and terminates at its lower end at a point, in the present instance, opposite the chamber 87.

Confined between the tube 102 and the inner wall of the bonnet 97 and finding a slide bearing on both of these parts is a sleeve 104, and this sleeve extends downwardly through the chamber 86 and into the draft tube sleeve 91, and terminates at its lower end in a conical extension 105 which occupies a position within the draft tube 89. The lower portion of the sleeve 104 above the extension 105 closely fits the inner cylindrical wall of the sleeve 91, and a beveled shoulder 106 at the inner end of the said extension 105 is adapted to seat against a reversely formed shoulder 107 in the sleeve 91 immediately below the ports 88, thereby to normally and positively seal these ports as shown. The sleeve 104 is also provided with a shoulder 108 which is adapted to seat normally upon the upper end of the sleeve 91, the function of this shoulder being hereinafter described. It will be noted that the sleeve 104 when in the said normal position, as shown in Fig. 9, constitutes an inner sealing wall for the exhaust steam chamber 86. Below the shoulder 108 the sleeve 104 is provided with an annular series of ports 109, which ports in the normal depressed position of the sleeve, as illustrated, are arranged to overlap a corresponding series of ports 111 in the sleeve 91, these latter ports giving access to an annular chamber 112 in the casing 81 which extends downwardly around the water chamber 87 and at its lower end communicates through ports 113 with the space surrounding the lower end of the draft tube 89 and with the interior of a vacuum tube 114 which embraces the extension 89 and extends below the terminal end of the latter. As illustrated, the upper cylindrical portion of the vacuum tube 114 through which the ports 113 extend closely fits the inner wall of the casing 81, and is threaded onto the draft tube 89. The vacuum tube 114 terminates at its lower end in the interior of a combining tube 115 which seats against a shoulder 116 in the lower end of the casing 81, and into the upper end of this combining tube the vacuum tube is threaded.

The upper end 104a of the sleeve 104 which occupies the interior of the bonnet 97 has threaded therein a (one or more) stem 117 which constitutes a retainer for a coiled spring 118. The stem 117 and the spring 118 extend upwardly through an opening in the top of the bonnet 97 and into the interior of a cylindrical casing 119, which in the present instance is integral with and extends upwardly from the top of the bonnet 97 through the chamber 85 and has at its upper end a reduced cylindrical extension 121 which passes through a suitably sealed opening in the cover 81a of the casing 81. The extension 121 extends beyond the top of the cover 81a and is threaded for reception of a nut 122. The extension 121 is hollow and is interiorly threaded for reception of a screw 123 which extends downwardly into the spring casing 119 and against the top of an upper

spring retainer 124 which is slidable in the casing and which engages in the upper end of the spring 118. The arrangement provides for adjustment of the spring to regulate the compressive force exerted thereby against the upper end of the sleeve 104, which force tends to resiliently retain the said sleeve 104 in the depressed position in which it is shown in the drawings.

Between the sleeve 94 and the bonnet 97 is provided an annular chamber 125, the upper end of which communicates with a port 126 which extends inwardly through the wall of the bonnet, and the inner end of this port 126 is normally closed by the upper end 104a of the sleeve 104 when the said sleeve is in the normal depressed position as illustrated. The lower end of the chamber 125 is in communication with the exhaust chamber 86 through a port or ports 127 formed between the lower extremity of the bonnet 97 and the inner wall of the sleeve 94.

The bonnet 97 is provided at opposite sides with ports 128 and 129, the port 128 communicating at its upper end, through a port 131 in the upper threaded extremity of the tube 102, with the interior of that tube; and the port 129 communicating similarly with the interior of the tube 102 through a port 132 in the upper end of the latter. The lower end of the port 128 is adapted to communicate with the upper end of a port 133 in the sleeve 104 when the latter is in the normal depressed position, the port 133 extending downwardly to an annular chamber 134 which is formed between an inwardly extending shoulder 135 on the sleeve 104 and a reverse shoulder 136 in a flange 137 which extends outwardly from the side of the tube 102 and against the inner wall of the sleeve 104. From the bottom of the chamber 134 a small port 138 extends downwardly to the space below the flange 137 and to the interior of the tube 104. The lower end of the port 129, as illustrated in the drawings, is closed by the sleeve 104 when the latter is in the depressed position, and this sleeve 104 has in its wall a pear-shaped port 139, see Fig. 10, which is in line with and normally below the lower end of the port 129, so that when the sleeve 104 is lifted, as hereinafter described, the port 139 is brought into registration with the lower end of the port 129. The inner end of the port 139 communicates with an annular chamber 141 formed between the tube 102 and the inner wall surface of the sleeve 104, the upper end of this chamber 141 being formed by a flange 142 projecting from the tube 102 and fitting slidably against the inner wall of the sleeve 104; and the bottom wall of the chamber 141 being formed by the upper surface of the projecting flange 137 of the tube 102. From the bottom of the port 139 a channel 140 extends downwardly through the wall of the sleeve 104 to the shoulder 135, thereby communicating with the chamber 134. In the lower end of the chamber 141 ports 143 extend downwardly through the flange 137 and establish communication between the said chamber 141 and the interior of the sleeve 104 at the upper end of the space between said sleeve and the lower end of the tube 102.

Above the port 133 the sleeve 104 is channeled longitudinally to provide an elongated port 144 which is in line with the inner end of the port 126, and the upper end of the port 144 extends inwardly through the sleeve 104 to communicate at its inner end with an annular chamber 145 formed between the flange 142 of the tube 102 and

the under side of the upper end portion 104a of the sleeve 104. As previously set forth, the port 126 is normally closed at its inner end by the said upper sleeve portion 104a, but when the sleeve is elevated sufficiently, the port 126 is connected with the port 144, and through this port with the chamber 145.

The lock nut 103 at the upper end of the tube 102, in addition to its locking function, is adapted also to form a seat for a valve 146, which valve when closed, as shown in full lines in Fig. 9, prevents admission of the high pressure steam in the chamber 85 to the interior of the tube 102. The stem 147 of the valve 146 extends upwardly through the cover member 81a of the casing 81 through a suitable packing joint 148 in the latter. The valve 146 also has a depending stem 149 which extends downwardly into the upper end of the tube 102, the portion of this stem 149 immediately below the valve 146 being of a diameter less than the interior diameter of the upper end of the tube 102, and the lower extremity 151 of the stem 149 being of increased diameter and in the present instance (though not necessarily) neatly fitting the cylindrical interior of the upper end of said tube. The stem 149 has a transverse port 152 extending from one side of the said stem to the other, and a central port 153 which extends downwardly from the center of the port 152 to the lower beveled extremity 151 of the stem. It will be apparent, therefore, that when the valve 146 is elevated from its seat on the lock nut 103, live steam from the chamber 85 will be permitted to flow past the reduced portion of the stem 149 to the ports 128 and 129, and also through the ports 152 and 153 into the upper end of the tube 102. An initial slight elevation of the valve 146 will permit limited flow of the live steam to said ports, and when the valve 146 is fully elevated so that the lower end of the stem 151 is carried clear of the upper end of the tube 102, as indicated in broken lines in Fig. 9, there is permitted a substantially free flow of the high pressure steam to the interior of the tube 102 and also to the ports 128 and 129. Manual means (not shown) is provided for actuating the valve 146.

In the normal operation of the device, the valve 146 is first elevated slightly from its seat to admit steam from the chamber 85 to the ports 128 and 129, and through the ports 152 and 153 as previously described to the interior of the tube or nozzle 102. The high pressure steam passing through the ports 128 and 133 to the chamber 134 has the effect of elevating the sleeve 104 to a position of initial lift, wherein the ports 83 are opened to admit water to the interior of the draft tube 89. The high pressure steam initially entering and passing through the tube 102 has a desirable priming effect upon the device. This initial lift of the sleeve valve 104 also brings the port 139 into registration with the lower end of the port 129, and admits high pressure steam to the chamber 141, and through the ports 143 to the interior of the sleeve 104, this steam passing downwardly to and through the coned lower end of the sleeve and combining with the water in the draft tube 89. Initial lift under pressure of high pressure steam cannot extend beyond the point where the shoulder 135 reaches the level of the shoulder 141a which forms the bottom wall of the chamber 141.

It will be noted further that the steam entering the interior of the sleeve 104 through the

ports 143 is permitted to pass through the ports 109, or through a supplemental series of ports 109a in the sleeve 104, through the ports 111 to the chamber 112, and from this chamber through the ports 113 to the interior of the vacuum tube 114, this component of the high pressure steam being condensed by the water jet and aiding in the formation of the vacuum required to develop the necessary high velocity of the water jet delivered, as hereinafter described, by the injector. It will be noted that the two series of ports 109 and 109a are so relatively arranged that one or other of these series of ports is in a position to establish communication between the interior of the sleeve 104 and the chamber 112, so that this connection is continuous regardless of the position of the sleeve.

Following the initial limited elevation of the valve 146 and the resulting prime operation, the operator elevates the valve 146 to its extreme position, as indicated in dotted lines, to thereby permit the free flow of high pressure steam to the tube 102 and to the ports 128 and 129.

The initial lift of the sleeve valve 104 as described elevates the shoulder 108 from its seat on the upper end of the sleeve 91, and also brings the port 144 into communication with the port 126, whereby exhaust steam from the chamber 86 passing upwardly through the port 127 into the chamber 125 is permitted to flow through the ports 126 and 144 to the chamber 145. If now the pressure of exhaust steam is sufficiently great, acting on the lift surfaces at the top of the chamber 145 and under the shoulder 108, to overcome the resisting and opposing forces including the pressure of the spring 118, the steam from that source will still further elevate the sleeve 104, thereby disconnecting the port 133 from the port 128, and the port 139 from the port 129. At the same time, this additional lift will carry the ports 109 into communication with the exhaust steam chamber 86, and will permit a direct flow of the exhaust steam from this chamber to the interior of the sleeve 104. Similarly, through the ports 109a the exhaust steam will be permitted to pass to the chamber 112, and from this chamber through the ports 113 to the interior of the vacuum tube 114. Thus the live steam previously passing into the interior of the sleeve 104 and through the chamber 112 to the vacuum tube 114 will be replaced by exhaust steam, which takes over the function of the high pressure steam with a resulting economy of the latter. The injector now operates on an exhaust steam basis, and this operation will be continued as long as the exhaust steam pressure is sufficiently great to maintain the sleeve valve 104 in the elevated position. If the exhaust steam pressure is reduced to an extent permitting the sleeve to fall, the live steam is again brought into action to maintain the sleeve in the position of initial lift, wherein the injector operates solely on the high-pressure steam.

When the device is operating on the high-pressure steam basis, it is only necessary, in order to discontinue the operation of the injector, to manually close the valve 146. If, however, it is desired to discontinue the operation of the injector when the latter is operating on the exhaust steam basis, it is necessary not only to close the valve 146, but also either to shut off the exhaust steam from the chamber 86 or to forcibly return the sleeve valve 104 to its de-

pressed or normally seated position. For this latter purpose, I have provided at the top of the bonnet 97 a plunger 154 which extends downwardly through an opening in the top of the bonnet and which is slidably housed within a cylindrical casing 155 extending upwardly from the top of the bonnet through the casing cover 81a, this housing being similar in form and mode of attachment to the casing 119 previously described, but including in addition a suitable packing joint 156 through which the stem 157 of the plunger 154 extends. This plunger may be moved downwardly by manual means to engage the upper end of the sleeve valve 104 and to force the said sleeve downwardly to its normal depressed or seated position wherein the passage of exhaust steam from the chamber 86 through the ports 109 is prevented. It will be noted that I have provided in the plunger 154 a passage or port 158 shown in dotted lines which extends longitudinally through the plunger to establish communication between the upper interior space 90 of the bonnet 97 and the atmosphere whereby the sleeve 104 is permitted to move upward into the otherwise closed upper end of the bonnet, and whereby also the exhaust steam operating on the lift surfaces of the sleeve valve 104, as previously described, may be effective to elevate the sleeve. Leakage of steam between the sleeve 104 and the wall of the bonnet 97 into the chamber 90 is largely prevented by packing ring 150, and by the further fact that high pressure steam from the passage 129 tending to leak between the sleeve and the bonnet wall may escape readily by way of the port 139 to the low pressure chamber 141; or in event that the inner end of the port 139 is blocked by the flange 142, the high pressure steam leakage may still pass freely to the chamber 141 by way of the channel 140.

The channel 140 has a further valuable function in providing recoil action of the high pressure steam to eliminate undesirable inertia effects in the movements of the sleeve 104. The component of the high pressure steam entering the channel exerts a reactionary lift force upon the sleeve which in amount depends upon the cross-sectional area of the channel and the degree of restriction of the inner end of the port 139.

In Fig. 11 I have illustrated a modification which in effect increases the effective areas of the exhaust steam lift surfaces of the sleeve valve 104 with respect to the counter pressure areas of that sleeve. The construction is the same as that shown in Fig. 9, with the exception that the sleeve 104 is of somewhat greater thickness above the shoulder 103, so that the effective area of this shoulder may be increased without, however, increasing the effective counter pressure areas. This arrangement renders the device more sensitive to operation by the exhaust steam fed to the chamber 86 as previously described. The principle of operation of the device, however, remains unchanged.

It will be apparent from the foregoing description that by this invention I have provided in a single compact unit an exhaust steam injector of the single-line type, wherein through the medium of a single movable member a fully automatic control and regulation is afforded, not only of the steam admission but also of the water supply, and wherein further the changeover from high pressure to exhaust steam operation, and vice versa, is effected automatically and directly in accordance with the ability of the exhaust steam source to supply the requirements of the

injector. It is to be noted further that by reason of the unified control of the water and steam admission, the device affords an automatic interregulation of the flow of these two fluids to the injector, and this interregulation is such in the case of the exhaust steam as to automatically compensate for the unavoidable fluctuations in the pressure from the exhaust steam source. Thus when the exhaust steam pressure is relatively low and the sleeve valve 104 assumes an intermediate lift position, the effective area of the water admission ports 88 will be relatively small, and when the pressure of the exhaust steam is relatively great and the sleeve valve accordingly takes a position of extreme lift, the area of the exhaust ports will be correspondingly increased to thereby synchronize the admission of water with the relatively great quantity of available exhaust steam. It will be noted further that in this device the various elements of the injector are arranged around a common longitudinal center line, and that the single moving element works along this line, so that all undesirable or detrimental side pressures and lifts are avoided. Attention is also directed to the fact that the admission of all fluids involved in the operation of the injector and in the automatic actuation, including also the high pressure steam admission to the tube 102, is controlled by the manually-operated valve element 146, and that by reason of the fully automatic control and regulation of the device as described, this valve member 146 constitutes the sole necessary manual control, with the exception only of the plunger 154, which, as previously described, is not required when the device is operating solely on high-pressure steam, and may, in fact, be eliminated in favor of a valve for controlling the passage of exhaust steam to the exhaust steam chamber 86.

In describing and illustrating my invention, I have disclosed only those portions of the injector which are necessary to a proper understanding of the invention, it being understood that beyond the vacuum tube 114 and the combining tube 115, which are conventional elements of a steam injector of this specific type, the injector device will also include the conventional delivery cone and associated parts. It will be understood also that there may be considerable modification in detail of construction without departure from the invention. While, for example, I have illustrated a single spring 118 for normally retaining the sleeve valve 104 in its depressed or seated position, there may be and preferably is a plurality of such springs arranged to afford an accurately balanced device, and the construction as illustrated obviously affords adequate available space for this purpose. It is to be noted further, for example, that the port 153, the function of which is to admit a priming jet of high-pressure steam to the tube 102 when the valve 146 is initially elevated, may be eliminated, as this is not essential to the operation of the device, although desirable for priming purposes as described.

I claim:

1. In a steam injector the combination with a casing having a discharge opening and ports for admission of water and of steam from both high pressure and exhaust sources, a steam nozzle arranged for communication with said steam ports, and a draft nozzle arranged in advance of said steam nozzle for communication with the said water port, a valve member movably mount-

ed in said casing and operative with respect to said ports and constituting thereby a common means for directly controlling passage to said nozzles of the steam and water admitted to the casing through said ports, means providing separate primary and secondary lift chambers between said valve member and relatively fixed portions of the casing in which chambers fluid pressure may act to move the valve, means for initially connecting the said primary chamber with the high pressure steam port to thereby move the valve to an initial lift position providing a passage for steam from the high pressure source to the steam nozzle and admitting water to the draft nozzle, means operative in said initial lift position of the valve to connect said secondary lift chamber with the exhaust steam port whereby the steam from the exhaust source may further lift the valve to admit exhaust steam to the steam nozzle and to close the said high pressure steam passage.

2. A steam injector having individual ports for admission thereto of water, live steam, and exhaust steam; a steam nozzle arranged for communication with said steam ports; a draft nozzle arranged for communication with said water port; a composite valve member adapted to cover the said several ports to thereby prevent flow therethrough of water and steam to said nozzles, and being movable to uncover said ports so as to afford a simultaneous flow of water and steam to the respective nozzles; said steam ports being arranged with respect to each other and to the valve so as to afford a selective opening of said live and exhaust steam ports; means actuated by fluid pressure from the live steam source for moving the valve to an initial position wherein water is admitted to the draft nozzle and live steam to the steam nozzle to the exclusion of exhaust steam; and means adapted for actuation by fluid pressure from the exhaust steam source for further moving the valve to a secondary position admitting exhaust steam to said steam nozzle to the exclusion of live steam.

3. A steam injector comprising a main steam nozzle; a draft nozzle; individual ports for admission of live and exhaust steam respectively to said steam nozzle; a port for admission of water to the draft nozzle; a composite valve member directly operative on all of said ports for controlling and regulating admission therethrough to the respective nozzles of water, live steam, and exhaust steam; a supplemental steam nozzle; manually-operated valve means for controlling the passage of live steam to said supplemental nozzle and to the said live steam admission port; means operative automatically upon the opening of said manual valve for moving said composite valve by fluid pressure from the live steam source to an initial position wherein the live steam is admitted through said admission port to the main steam nozzle and water to the draft nozzle while excluding exhaust steam from the said steam nozzle; and means operative when the composite valve is in the said initial position and by fluid pressure from the exhaust steam source to further move the composite valve to a secondary position wherein the said live steam admission port is closed and the said exhaust steam admission port is opened to admit exhaust steam to the main steam nozzle.

4. A steam injector comprising a main steam nozzle; a draft nozzle; individual ports for admission of live and exhaust steam respectively to

said steam nozzle; a port for admission of water to the draft nozzle; a composite valve member directly operative on all of said ports for controlling and regulating admission therethrough to the respective nozzles of water, live steam, and exhaust steam; a supplemental steam nozzle; manually-operated valve means for controlling the passage of live steam to said supplemental nozzle and to the said live steam admission port; means operative automatically upon the opening of said manual valve for moving said composite valve by fluid pressure from the live steam source to an initial position wherein the live steam is admitted through said admission port to the main steam nozzle and water to the draft nozzle while excluding exhaust steam from the said steam nozzle; means operative when the composite valve is in the said initial position and by fluid pressure from the exhaust steam source to further move the composite valve to a secondary position wherein the said live steam admission port is closed and the said exhaust steam admission port is opened to admit exhaust steam to the main steam nozzle; and means for returning said composite valve to a position closing said water admission port.

5. A steam injector comprising a main steam nozzle; a draft nozzle; individual ports for admission of live and exhaust steam respectively to said steam nozzle; a port for admission of water to the draft nozzle; a composite valve member directly operative on all of said ports for controlling and regulating admission therethrough to the respective nozzles of water, live steam, and exhaust steam; a supplemental steam nozzle; manually-operated valve means for controlling the passage of live steam to said supplemental nozzle and to the said live steam admission port; and fluid-pressure means operative automatically upon the opening of said manual valve for actuating said composite valve by fluid pressure from said live and exhaust steam sources to effect a controlled and interregulated flow of steam and water to the said main steam and draft nozzles, said fluid-pressure means comprising pressure chambers operatively associated with said composite valve for live and exhaust steam respectively in which chambers said steam is operative to shift the said valve; means operative when said manual valve is opened for admitting live steam to the first of said pressure chambers to thereby shift the composite valve to an initial position admitting water to the draft nozzle and live steam through said admission port to the said main steam nozzle; means for limiting the extent of said initial shifting of the valve by the live steam; means operative in said initial position of the valve to connect said secondary lift chamber with the exhaust steam port whereby the steam from the exhaust source may further shift the valve beyond said initial position; and means for interrupting the flow of live steam through said admission port and for admitting exhaust steam through the exhaust steam admission port to the main steam nozzle when the composite valve is shifted by exhaust steam pressure beyond said initial position.

6. A steam injector comprising a main steam nozzle; a draft nozzle; individual ports for admission of live and exhaust steam respectively to said steam nozzle; a port for admission of water to the draft nozzle; a composite valve member directly operative on all of said ports for controlling and regulating admission therethrough to the respective nozzles of water, live

steam, and exhaust steam; a supplemental steam nozzle; manually-operated valve means for controlling the passage of live steam to said supplemental nozzle and to said live steam admission port; and fluid-pressure means operative automatically upon the opening of said manual valve for actuating said composite valve by fluid pressure from said live and exhaust steam sources to effect a controlled and interregulated flow of steam and water to the said main steam and draft nozzles, said fluid-pressure means comprising pressure chambers operatively associated with said composite valve for live and exhaust steam respectively in which chambers said steam is operative to shift the said valve; means operative when said manual valve is opened for admitting live steam to the first of said pressure chambers to thereby shift the composite valve to an initial position admitting water to the draft nozzle and live steam through said admission port to the said main steam nozzle; means for limiting the extent of said initial shifting of the valve by the live steam; means operative in said initial position of the valve to connect said secondary lift chamber with the exhaust steam port whereby the steam from the exhaust source may further shift the valve beyond said initial position; means for interrupting the flow of live steam through said admission port and for admitting exhaust steam through the exhaust steam admission port to the main steam nozzle

when the composite valve is shifted by exhaust steam pressure beyond said initial position; and pressure means acting on said composite valve in opposition to said steam pressures and tending to return the said valve to the normal position of admission-port closure.

7. A steam injector comprising a steam nozzle; a draft nozzle; individual ports for admission of live and exhaust steam respectively to said steam nozzle; a port for admission of water to the draft nozzle; a valve member operative with respect to said ports and constituting thereby a common means for directly controlling passage to said nozzles of steam and water through said ports; means providing separate primary and secondary lift chambers in operative association with said valve member in which chambers fluid pressure may act to move the valve; means for initially connecting the said primary chamber with the live steam port to thereby move the valve to an initial lift position providing a passage for steam from the live steam source to the steam nozzle and admitting water to the draft nozzle; and means operative in said initial lift position of the valve to connect said secondary lift chamber with the exhaust steam port whereby the steam from the exhaust steam source may further lift the valve to admit exhaust steam to the steam nozzle and to close the said live steam port.

EUGENE Y. GUTHMANN.
